UNITED STATES PATENT OFFICE.

ALFRED LEE, OF PAULDING, OHIO, ASSIGNOR OF ONE-HALF TO FRANCIS B. DE WITT, OF SAME PLACE.

FRICITION RATCHET-MOTOR.

SPECIFICATION forming part of Letters Patent No. 255,389, dated March 21, 1882.

Application filed January 14, 1882. (No model.)

To all whom it may concern:

Be it known that I, ALFRED LEE, a citizen of the United States of America, residing at Paulding, in the county of Paulding and State 5 of Ohio, have invented certain new and useful Improvements in Friction Ratchet-Motors; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 The object of my invention is to provide simple, compact, and serviceable means for converting reciprocating motion into rotary, whereby power transmitted by an ordinary treadle may be caused to operate rotating 20 mechanism; and my invention relates to that description or class of means for the above purposes which may be denominated as "friction ratchet-motors;" and my invention consists in a motor of the class mentioned which has 25 certain characteristics of construction and operation, as hereinafter more fully described, and specifically set forth in the claims.

Figure 1 is a perspective of my motor. Fig. 2 is a vertical section thereof, and Figs. 3, 4, 30 and 5 are details.

Like letters of reference indicate like parts in all the figures.

My invention is designed to be used in connection with the treadle and main or driving 35 shaft of lathes, sewing-machines, and all other mechanisms run by foot-power, and I have shown only the main shaft A and treadle F as being sufficient to render the use and operation of my invention clear.

40 To the main shaft A, by set-screw a, the fixed section B of my motor is secured.

The movable section C of my motor is retained from longitudinal movement on shaft A by contact with fixed section B, and with a 45 collar or shoulder, a', on the shaft, as shown. Otherwise it is loosely fitted on the shaft.

The section B is provided with a concentric straight-walled groove, b, and section C is provided with a flange, c, which is continuous except 50 at C', a small portion of the flange being re-

moved at that point for the reception and operation of the free end of the ratchet-bar D, the ratchet-lug d thereof being adapted to ride in the groove b of section B. The bar D is bent at the center to form a depression, d', 55 which passes or loosely fits about the shaft A, between which and the bar a slender spring, d'', of sheet-steel is placed.

To the section C is attached means by which it may be rotated partially or wholly, and if 60 partially or intermittently rotated additional means may be used to return it to, or about to, the point of starting; and though I have shown one form of means for the above purposes, I do not desire to limit myself, so far 65 as the construction of the motor proper as above described is concerned, to the said means, as other forms and arrangement of the same may readily be attached by persons possessing ordinary mechanical skill.

To the section C, I may apply a belt, G, attached at g, the other end of the belt being attached to a coil-spring, H, which is secured to any desired fixed part of the machinery to be operated, and to the hub of said section, in 75 like manner, I attach the ordinary treadle-strap or band, E.

The operation of my motor is as follows: The free end of the treadle being depressed, the strap E turns section C in one direction, 80 and upon the removal of pressure on the treadle-spring H and strap G turns the section in the opposite direction. The ratchet-bar D is by spring d'' caused to lie in such a position that its lug d is wedged in the groove 85 b—that is, the lug in its longer dimension is disposed diagonally in the groove, so that its front inner and rear outer corners bite against the inner and outer walls of the groove. When section C is reversed in movement by strap G, 90 the end of the flange of section C strikes against the free end of ratchet-bar D and overcomes the pressure of spring d'', and thus causes the lug d to be aligned with the groove b, when it moves freely therein and allows the fixed section and shaft to continue the forward rotation imparted to it, while section C and the ratchet-bar are backwardly rotated to again be used in imparting further rotation to the shaft.

It will be observed that my motor is not only 100

exceedingly simple, but very compact, of smooth exterior and without projecting elements, and the parts, while being all contained within, are of easy construction and great strength.

5 I am aware that the following constructions are not of my invention, viz: two disks mounted upon a stationary non-rotative stud with an intermediate lever adapted to bite in a groove of one of said disks, and extending 10 beyond the periphery and biting on the said periphery of another disk, and two disks, one of which is provided with a pawl which takes into a circular ratchet constituting a part of the other disks; but,

15 Having described my invention and its operation, what I claim as new, and wish to secure by Letters Patent, is—

1. The combination of section C and straps

E and G, with means for operating the same in opposite directions with section B, and 20 means contained within the limits of said sections and yieldingly held away from the shaft A by an intermediately-arranged spring, for operating said shaft, all substantially as shown and described.

2. The combination of shaft A, sections B and C, ratchet-bar D, spring d^2 , straps E and G, spring H, and treadle F, substantially as 25 shown and described.

In testimony whereof I have affixed my signature in presence of two witnesses.

ALFRED LEE.
